UNITED STATES PATENT OFFICE

WILLIAM J. BAUER, OF NEW YORK, N. Y., ASSIGNOR TO PROJECT HOLDING CORPORATION, OF NEW YORK, N. Y., A CORPORATION OF NEW YORK

COLLAPSIBLE CHAIR

Application filed May 5, 1928. Serial No. 275,333.

The invention relates to chairs, more particularly of the automatic folding or collapsible type suitable for compact storage when desired. It has for its object to provide, in a chair of this character, means whereby the seat portion thereof may have independent movement and be caused to assume a position between its normal horizontal operative location and the back portion of said chair when the latter is in extended condition. This feature is of particular value when the chair is used in halls, auditoriums, etc., especially in groups of two or more individual chairs arranged in rows, as it enables ready passage in and out between successive rows of the chairs whose occupants may then temporarily stand more or less within the chair itself.

The invention has for its object, also, certain features of construction which simplify the chair, for example, it dispenses with the use of any gearing or like mechanism for effecting the separation of the leg members of the chair, as in the manner set forth in my copending application, Serial No. 225,439.

In carrying out my invention, as embodied in the novel collapsible chair, a rear pair of legs is pivotally secured at the respective upper ends to rearward extensions of the front pair of legs, the seat member of the chair being hingedly attached along its rear edge, for example, to a rod which is mounted for longitudinal movement in the said rear pair of legs. Supporting means, as spring-urged plungers, to this end are movably mounted therein and project at their lower or outer ends beyond the corresponding lower ends of the rear pair of chair legs to engage with the surface upon which the chair is to be supported.

Moreover, a stop bar is arranged in front of said rod, being mounted between the front pair of legs and pivotally attached thereto, the seat resting thereon in normal position. Straps or like expedients are also provided to connect the said bar with the rod, being pivoted or hinged at their junction with the latter.

In addition, means are included for automatically locking or holding the said seat in

a more or less vertical plane to assume a position intermediate its normal horizontal location and the chair back, said means becoming effective merely upon manually raising the said seat and acting, further, to maintain the seat securely within the plane of the legs of the chair when the latter is collapsed.

The nature of the invention, however, will best be understood when described in connection with the accompanying drawings, in which:

Fig. 1 is a perspective view of the novel chair in open condition ready for use.

Fig. 2 is a longitudinal section on an enlarged scale through a rear leg of the chair.

Fig. 3 is a front elevation of the chair in collapsed or folded condition.

Fig. 4 is a vertical section of the chair in open condition, showing the seat thereof in the intermediate raised position.

Fig. 5 is a fragmentary enlarged detail view illustrating the manner of connecting the seat between the two pairs of legs.

Fig. 5a is a fragmentary vertical section taken on the line 5a—5a, Fig. 5.

Fig. 6 is a horizontal section taken on the line 6—6, Fig. 5 of the drawings, and looking in the direction of the arrows.

Referring to the drawings, the novel chair comprises a rigid, one-piece outer frame, for example, the inverted U-shape piece 10 which constitutes the pair of front legs whose extensions form the supporting frame for the back portion 11 of the chair. A pair of rear legs 12 is designed to fit within the frame 10 and these leg members are pivotally attached at their upper ends, which extend above the chair seat member 13, to the said extensions of the front pair of legs. A rung member 14 may be secured across the lower extremities of the pair of rear legs 12, but it is preferred to construct the pair of front legs of sufficient rigidity not to require such rung and so allow an occupant to enter more or less within the chair when the seat is elevated, as herein-after set forth.

This seat is mounted in a novel manner so as to permit movement of the same independently of the supporting pairs of legs and such as not to interfere with the collapse and

extension of the chair as a whole; and the same, furthermore, is adapted to be slidably mounted relatively to the pair of rear legs. To this end, a rod 15 extends between the same, the ends of the rod being mounted in recesses 16 of plungers 17 sliding within the legs 12 which are tubular to receive said plungers. The said rod is to be held thereby against rotation, for example, by squaring its ends, as shown, and forming the recesses 16 accordingly, while the inner face of each leg is slotted longitudinally downward so that said rod may be depressed when the chair is to be collapsed. The extent of its upward movement is determined by stops 18 at the upper end of the slots and projecting inwardly from the respective leg members, the same being adapted to contact with the rod ends when the seat attains the proper level.

Rod 15, moreover, passes freely through the rear portion of said seat, or rather the downturned flange or rim 19 thereof, so that said seat is swingably mounted thereon at this portion and indirectly supported by the said pair of rear legs through the plungers 17 thereof. The outer ends of the latter project beyond the corresponding lower ends of the legs 12 to contact with the floor or other support for the chair; and when the latter is in the collapsed state, as indicated in Fig. 3, said plungers will project an appreciable distance beyond the leg extremities, being positively urged outwardly through the medium of a spring 20 coiled about the upper reduced end 21 of each plunger and bearing against a shoulder 22 thereof.

The seat 13 is also connected to and adapted to be supported by the pair of front legs 10, for example, through a bar 25 pivotally connected to the said legs between the same and at the desired height for the said seat; and by a pair of straps 26 or the like which are rigidly secured to the said bar and extend rearwardly to hinge about the rod 15 which is provided with cylindrical portions 15' over which the straps 26 are turned. By this expedient, the two pairs of legs are free to swing relatively to each other to bring the rear pair substantially within the plane of the front pair, the seat 13 swinging upwardly therewith and at the same time moving downwardly at the rear portion to occupy a position in the same plane, as indicated in Fig. 3.

Stop means as the finger 27, secured to the underside of the seat are adapted to contact with the legs 12 on the return or inward movement of the seat and project laterally from opposite sides of said seat to prevent the same from swinging backwardly beyond the plane of the pair of front legs; and the bar 25 is provided with the longitudinal slots 23 to accommodate said fingers when the seat is in its lowered operative location. Moreover, a pair of buffers 29 may be provided on

the underside of the seat, for example, adjacent the fingers 27, to cushion the seat when the same is lowered.

As the said seat is thus movable up and down independently of the leg members, provision has been made to retain the same in a more or less elevated position intermediate its normal horizontal location and the back of the chair. To this end, a resilient plate 30 may be rigidly attached to the underface 75 of the seat with projecting portion or tongue 31 thereof designed to bear upon the flattened surface 32 of the rod 15. This will serve to maintain the seat in its elevated or semi-elevated position to allow of convenient 85 passage between successive rows of these chairs; and since no rung member is necessary across the lower portion of the pair of front legs 10, an occupant of the chair may stand well within the chair itself to allow 85 others to pass.

A further flattened face 33 is provided on the rod 15 for engagement with the resilient plate 30 to assist in maintaining the seat within the plane of the two pairs of legs when 90 said chair is extended; and resilient locating fingers 34 adjacent the tongue portion 31 are provided on the said plate to ride in circular transverse grooves 35 over the periphery 95 of the rod to restrict lateral play of the seat. 95

In extending the chair for use, the two pairs of legs are separated by pressing downwardly and forwardly on the rear pair to force the respective plunger elements inwardly, this having the effect, also, of moving outwardly the seat member through its rod engagement with the said plunger and locates it in its intermediate position. Thereupon, when the leg members are positioned, the seat may be manually lowered to the horizontal location indicated in Fig. 1. In collapsing the chair, this may conveniently be effected either by swinging the seat manually inwardly to its limit while raising the chair, or merely by lifting the chair from the 100 ground or support, the spring-urged plunger serving to draw the seat to its innermost position.

I claim:

1. A collapsible chair, comprising a pair 115 of front legs, a pair of rear legs pivotally secured at their respective upper ends to extensions of the front pair of legs and adapted to fit within the same, a seat swingably carried along its rearward portion by the rear 120 pair of legs and movable longitudinally thereof, means slidably relatively to the respective rear legs, projecting beyond their corresponding lower ends and adapted to support said seat, and a stop bar pivotally 125 secured to the front pair of legs and hingedly connected with the seat supporting means, said bar affording a support for an intermediate portion of the seat.

2. A collapsible chair, comprising a pair 130

of front legs, a pair of rear legs pivotally secured at their respective upper ends to extensions of the front pair of legs and adapted to fit within the same, a rod non-rotatably mounted in said rear pair of legs, a seat swingably carried along its rearward portion by said rod, means slidable relatively to the respective rear legs, projecting beyond their corresponding lower ends and supporting said rod, and a stop bar pivotally secured to the front pair of legs and hinged to said rod, said bar affording a support for an intermediate portion of the seat.

3. A collapsible chair, comprising a pair of front legs, a pair of tubular rear legs pivotally secured at their respective upper ends to extensions of the front pair of legs and adapted to fit within the same, a seat swingably carried along its rearward portion by the rear pair of legs and movable longitudinally thereof, plungers slidable relatively to the respective rear legs, projecting beyond their corresponding lower ends and adapted to support said seat, and a stop bar pivotally secured to the front pair of legs and hingedly connected with the seat supporting means, said bar affording a support for an intermediate portion of the seat.

4. A collapsible chair, comprising a pair of front legs, a pair of tubular rear legs pivotally secured at their respective upper ends to extensions of the front pair of legs and adapted to fit within the same, a seat swingably carried along its rearward portion by the rear pair of legs and movable longitudinally thereof, plungers slidable relatively to the respective rear legs, projecting beyond their corresponding lower ends and adapted to support said seat, resilient means acting on said plungers to force the same normally outward, and a stop bar pivotally secured to the front pair of legs and hingedly connected with the seat supporting means, said bar affording a support for an intermediate portion of the seat.

5. A collapsible chair, comprising a pair of front legs, a pair of rear legs pivotally secured at their respective upper ends to extensions of the front pair of legs and adapted to fit within the same, a rod non-rotatably mounted in said rear pair of legs, a seat swingably carried along its rearward portion by said rod, plungers slidable relatively to the respective rear legs and projecting beyond their corresponding lower ends, said plungers being recessed to receive the opposite ends of the rod, and a stop bar pivotally secured to the front pair of legs and hinged to said rod, said bar affording a support for an intermediate portion of the seat.

6. A collapsible chair, comprising a pair of front legs, a pair of rear legs pivotally secured at their respective upper ends to extensions of the front pair of legs and adapted to fit within the same, a rod non-rotatably

mounted in said rear pair of legs, a seat swingably carried along its rearward portion by said rod, plungers slidable relatively to the respective rear legs and projecting beyond their corresponding lower ends, said plungers being recessed to receive the opposite square ends of the rod, and a stop bar pivotally secured to the front pair of legs and hinged to said rod, said bar affording a support for an intermediate portion of the seat.

7. A collapsible chair, comprising a pair of front legs, a pair of rear legs pivotally secured at their respective upper ends to extensions of the front pair of legs and adapted to fit within the same, a seat swingably carried along its rearward portion by the rear pair of legs and movable longitudinally thereof, means slidable relatively to the respective rear legs, projecting beyond their corresponding lower ends and adapted to support said seat, a stop bar pivotally secured to the front pair of legs and hingedly connected with the seat supporting means, said bar affording a support for an intermediate portion of the seat, and stop members carried by the seat to limit the extent of backward movement of the same and adapted to fit within slots of the bar.

8. A collapsible chair, comprising a pair of front legs, a pair of rear legs pivotally secured at their respective upper ends to extensions of the front pair of legs and adapted to fit within the same, a seat swingably carried along its rearward portion by the rear pair of legs and movable longitudinally thereof, means slidable relatively to the respective rear legs, projecting beyond their corresponding lower ends and adapted to support said seat, a stop bar pivotally secured to the front pair of legs and hingedly connected with the seat supporting means, said bar affording a support for an intermediate portion of the seat, stop members carried by the seat, having buffer portions to limit the extent of backward movement of the same and adapted to fit within slots of the bar, and further buffer elements carried by the seat to contact with said bar.

9. A collapsible chair, comprising a pair of front legs, a pair of rear legs pivotally secured at their respective upper ends to extensions of the front pair of legs and adapted to fit within the same, a rod non-rotatably mounted in said rear pair of legs, a seat swingably carried along its rearward portion by said rod, means slidable relatively to the respective rear legs, projecting beyond their corresponding lower ends and supporting said rod, a stop bar pivotally secured to the front pair of legs, and straps connecting said bar with the rod and hingedly attached to the latter, said bar affording a support for an intermediate portion of the seat.

10. A collapsible chair, comprising a pair of front legs, a pair of rear legs pivotally secured at their respective upper ends to ex-

tensions of the front pair of legs and adapted to fit within the same, a rod non-rotatably mounted in said rear pair of legs, a seat swingably carried along its rearward portion by said rod, means slidable relatively to the respective rear legs, projecting beyond their corresponding lower ends and supporting said rod, a stop bar pivotally secured to the front pair of legs and hinged to said rod,
10 said bar affording a support for an intermediate portion of the seat, and a spring plate secured to the underside of the seat having an intermediate flattened surface and adjacent spring fingers, the former adapted
15 to engage a flattened surface of the rod and the latter circular grooves thereof.

11. A collapsible chair, comprising a pair of front legs, a pair of rear legs pivotally secured at their respective upper ends to extend
20 tensions of the front pair of legs and adapted to fit within the same, a rod non-rotatably mounted in said rear pair of legs, a seat swingably carried along its rearward portion by said rod, means slidable relatively to the respective rear legs, projecting beyond their corresponding lower ends and supporting said rod, a stop bar pivotally secured to the front pair of legs and hinged to said rod, said bar affording a support for an intermediate portion of the seat, and a spring plate secured to the underside of the seat and the rod being provided with two flattened surfaces adapted to be engaged by said plate respectively when the seat is in a position intermediate its normal horizontal location and the back of the chair and when the chair is in extended condition.

In testimony whereof I affix my signature.
WILLIAM J. BAUER.
